Primary Examiner — Shannon W Morgan*Assistant Examiner* — Aula Soroush(74) *Attorney, Agent, or Firm* — Dunlap Bennett & Ludwig PLLC(57) **CLAIM**

The ornamental design for a dog bed with a canopy, as shown and described.

DESCRIPTION

FIG. 1 is a perspective view of a dog bed with a canopy showing my new design;

FIG. 2 is a front elevation view thereof;

FIG. 3 is a rear elevation view thereof;

FIG. 4 is a left side elevation view thereof, wherein a right side elevation view is a mirror-image thereof;

FIG. 5 is a top plan view thereof;

FIG. 6 is a bottom plan view thereof; and,

FIG. 7 is a perspective view thereof, shown in an environment of use.

The broken lines in the drawings illustrate environmental structure that form no part of the claimed design.

1 Claim, 4 Drawing Sheets(56)
